(57) CLAIM

I claim the ornamental design for a container for food products, as shown and described.

DESCRIPTION

FIG. 1 is a perspective view of the container for food products showing my new design;

FIG. 2 is a reduced front view thereof;

FIG. 3 is a reduced right view thereof;

FIG. 4 is a reduced left view thereof;

FIG. 5 is a reduced rear view thereof;

FIG. 6 is a reduced top view thereof; and,

FIG. 7 is a reduced bottom view thereof.

1 Claim, 2 Drawing Sheets

FIG. 1

FIG. 2

FIG. 3

FIG. 4

FIG. 5

FIG. 6

FIG. 7
